M. W. ROBERTSON.
ELECTRICAL CONNECTOR.
APPLICATION FILED NOV. 19, 1917.

Patented July 27, 1920.

Maxwell W. Robertson, Inventor
By his Attorney
Franklin Hill.

UNITED STATES PATENT OFFICE.

MAXWELL W. ROBERTSON, OF BELLE HARBOR, NEW YORK, ASSIGNOR TO GODFREY P. SCHMIDT.

ELECTRICAL CONNECTOR.

1,347,590.

Specification of Letters Patent. Patented July 27, 1920.

Application filed November 19, 1917. Serial No. 202,736.

To all whom it may concern:

Be it known that I, MAXWELL W. ROBERTSON, a citizen of the United States, residing at Belle Harbor, L. I., in the county of 5 Queens and State of New York, have invented certain new and useful Improvements in Electrical Connectors, of which the following is a specification, reference being had therein to the accompanying drawing.

10 My invention relates to improvements in electrical connectors and has particular reference to and is illustrated in the accompanying drawings in its application to a connector adapted for use upon the brush 15 of an electrical machine such as a dynamo or motor. It is of the utmost importance in 20 connections of this kind to provide good electrical contact in order to insure ample conductivity for the transmission of current 25 through the connection.

In the accompanying drawings, I have 30 illustrated in Figure 1 in perspective, a carbon brush and double connector embodying an application of my invention. Fig. 2 is a 35 similar view showing a single connector. Fig. 3 is a perspective view partly broken away illustrating one method of forming the 40 end of the flexible member of the connector. Fig. 4 is a perspective view partly broken 45 away illustrating the construction of the carbon brush, and Fig. 5 is a perspective view 50 illustrating one of the parts of the connector.

55 6 indicates the lower part of the carbon brush which is adapted to rest upon the commutator of the machine and 7 the upper part which is preferably electro-plated. One side of the upper part is recessed to receive the L-shaped member 8 as shown in Fig. 2, the upper part 9 of the L-shaped 60 member extending over the top of the carbon brush as shown. The other side of the carbon brush is cut away as indicated at 10—10' and a hole is drilled through the brush as indicated at 11.

45 65 The end of the flexible member such as illustrated in Fig. 3 is terminated in a loop which is crushed flat to seat within the round recess 10 of the brush and this loop when crushed being rectangular in cross-

section engages all sides of said recess there- 50 by making good contact therewith. After the end of the flexible member has been introduced, the screw 12 is pushed through and engages the tapped hole 13 of the locking member 14 which thereupon presses the com- 55 pressed loop 15 of the flexible member shown in Fig. 3 tightly within the hole 10, and it will be observed that the offset 14' of the locking member 14 engages the cut-away portion 10' of the carbon brush thereby ex- 60 tending the contact surfaces while at the same time preventing the locking member 14 from turning when the screw 12 is turned down tight.

In the modification shown in Fig. 1, instead of forming a loop at the end of the flexible member shown in Fig. 3, the flexible member 15' is bent in the center being crushed flat to form the loop for engage- 65 ment beneath the locking member 14. 70

The free ends of the flexible members are 75 also preferably retained within clips such as 16—17, the former being for a single flexible connection as shown in Fig. 2 and the latter for a double connection as shown in Fig. 1. By having the flexible member enter 80 the clip 16—17 at right angles to the direction of the slot 18 thereof, the waist or shank of the clip is wider and stronger and the loop of the clip surrounding the end of 85 the terminal is naturally of greater depth, thus insuring not only better electrical connection but increased mechanical strength.

90 By constructing connections in the manner aforesaid, it has been found by actual test that the electric conductivity is increased materially. The offset 9 of the angle plate 8 also provides bearing surface and prevents wear upon the top of the carbon brush 7.

95 Of course it will be understood that various modifications may be made in the construction and arrangement of parts without departing from the spirit of the invention as claimed.

I claim:

In combination with the brush of a dynamic electric machine, a flexible connection

having a loop at one end, a recess in one side of said brush within which said loop is seated, a screw passing through said loop and said brush, a recess at the opposite side 5 of said brush and an L-shaped contact clip adapted to engage said last mentioned recess and extend over the top of said brush, a binder adapted to fit over said loop within said recess, said screw adapted to engage

said binder for drawing said clip, brush, and 10 flexible connection together.

In testimony whereof I hereunto affix my signature in the presence of two witnesses.

MAXWELL W. ROBERTSON.

Witnesses:

ANNA F. DUFFY,
THOMAS A. HILL.
